(57) CLAIM

The ornamental design for a right sensor wing, as shown and described.

DESCRIPTION

FIG. 1 is a front, top, and side perspective view of the right sensor wing showing the new design according to a first implementation.

FIG. 2 is a rear, bottom, and side perspective view of the right sensor wing showing the new design according to a first implementation.

FIG. 3 is a top view of the right sensor wing showing the new design according to a first implementation.

FIG. 4 is a bottom view of the right sensor wing showing the new design according to a first implementation.

FIG. 5 is a left side view of the right sensor wing showing the new design according to a first implementation.

FIG. 6 is a right side view of the right sensor wing showing the new design according to a first implementation.

FIG. 7 is a front view of the right sensor wing showing the new design according to a first implementation.

FIG. 8 is a rear view of the right sensor wing showing the new design according to a first implementation.

FIG. 9 is a perspective view of the right sensor wing showing the new design according to a first implementation within environmental structure.

FIG. 10 is a front, top, and side perspective view of the right sensor wing showing the new design according to a second implementation.

FIG. 11 is a rear, bottom, and side perspective view of the right sensor wing showing the new design according to a second implementation.

FIG. 12 is a top view of the right sensor wing showing the new design according to a second implementation.

FIG. 13 is a bottom view of the right sensor wing showing the new design according to a second implementation.

FIG. 14 is a left side view of the right sensor wing showing the new design according to a second implementation.

FIG. 15 is a right side view of the right sensor wing showing the new design according to a second implementation.

FIG. 16 is a front view of the right sensor wing showing the new design according to a second implementation.

FIG. 17 is a rear view of the right sensor wing showing the new design according to a second implementation; and,

FIG. 18 is a perspective view of the right sensor wing showing the new design according to a second implementation within environmental structure.

Within the drawings, the straight-line surface shading and stippling show the character and contour of the surfaces in the claimed design of the right sensor wing. The broken lines

show unclaimed portions of the right sensor wing, and thus form no part of the claimed design. Certain drawings include broken lines showing the environmental structure of a truck tractor unit to illustrate environmental aspects only and form no part of the claimed design. Any broken line illustration of environmental structure in the drawings is not part of the design sought to be patented.
